Primary Examiner—Robin Webster*Assistant Examiner*—Karen E. Patterson(74) *Attorney, Agent, or Firm*—Wolf, Greenfield & Sacks, P.C.(57) **CLAIM**

The ornamental design for a computer peripheral device, as shown and described.

DESCRIPTION

FIG. 1 is a side, top, perspective view of the computer peripheral device with surface ridges and connector ports thereof shown in phantom;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a bottom view thereof.

The broken lines showing of surface ridges and connector ports are for illustrative purposes only and forms no part of the claimed design.
